UNITED STATES PATENT OFFICE.

THOMAS E. HUTCHINS, OF BEATRICE, NEBRASKA.

BOILER-FLUE BLOWER.

No. 863,538.

Specification of Letters Patent.

Patented Aug. 13, 1907.

Application filed May 9, 1907. Serial No. 372,803.

To all whom it may concern:

Be it known that I, THOMAS E. HUTCHINS, a citizen of the United States, residing at Beatrice, in the county of Gage and State of Nebraska, have invented certain new and useful Improvements in Boiler-Flue Blowers, of which the following is a specification.

This invention has for its object an improved boiler flue blower of simple, durable and efficient construction which may be installed through the combustion chamber door without the necessity of any change in the wall, which will in its maintenance and operation effect economies in the consumption of fuel and other respects, as in the case of hose, which will tend to prolong the life of the boiler and improve combustion and minimize smoke and soot by insuring clean tubes at all times, and which will in operation, not necessitate the opening of the boiler front at any time.

With these and other objects in view as will more fully appear as the description proceeds, the invention consists in certain constructions, arrangements and combinations of the parts which I shall hereinafter fully describe and then point out the novel features in the appended claims.

For a full understanding of the invention and the merits thereof and also to acquire a knowledge of the details of construction of the means for effecting the result, reference is to be had to the following description and accompanying drawings, in which:

Figure 1 is a side elevation of my improved boiler flue blower, showing its application; Fig. 2 is an end elevation thereof; Fig. 3 is a detail perspective view of one of the steam nozzles; and, Fig. 4 is a detail perspective view of the header of blower, and its connections.

Corresponding and like parts are referred to in the following description and indicated in all the views of the drawings by the same reference characters.

Referring to the drawings, the numeral 1 designates a steam dome on the boiler and 2 a steam supply pipe for my improved flue blower, which is connected at one end to the steam dome and is provided at its other end with a horizontally extending branch 3 connected therewith by the stuffing box joints and mounted to rotate about its longitudinal axis in bearings 4, so as to constitute a hollow shaft. The said hollow shaft portion 3 of the supply pipe 2 passes through an opening 5 underneath of the door 6 of the combustion chamber of the boiler furnace, and the formation of this opening 5 is the only change necessary to accomplish the installation of my device. Inside of the combustion chamber is a stand pipe 7 which is connected at its lower end to the revolute shaft portion 3 of the supply pipe and which carries at its upper end a header 8, said header being provided with a series of laterally extending nozzles 9, the outer extremities of which are preferably flared as clearly illustrated in the drawings.

The header 8 is mounted to turn about a horizontal

axis in suitable stuffing box joints 11 in the upper end of the stand pipe 7 and its supporting stem carries a depending rod 12 by which the said header may be rotated. The said rod 12 passes downwardly through 60 and has free movement in the laterally projecting loop 13 swiveled on the outer end of a rod 14 which projects upwardly from and is secured to a rocking shaft 15 journaled in the opening 5 in suitable bearings, as shown, and outside of the door 6 the said shaft 15 has a 65 hand lever 16 secured to it, the said hand lever extending upwardly. Another hand lever 17 is secured at its lower end to the hollow shaft portion 3 of the supply pipe 2 and is provided with the ordinary hand detent adapted for engagement with the quadrant 18. 70

19 designates a globe or other type of valve which is provided in the supply pipe 2 so as to control the passage of steam therethrough.

20 designates a drain cock which is secured to the supply pipe 2 and which leads to the drain pipe 21 75 connected to the blow off pipe 22. The latter is provided with a globe valve 23. The series of steam nozzles 9 is located in juxtaposition to the ends of the boiler flues and is adapted to inject steam therethrough and is capable of being rotated about its axis in different 80 directions at angles of forty-five degrees from the vertical by manipulation of the hand lever 16 in an evident manner. The entire series of nozzles may be shifted from one vertically extending series of flues to the next by means of the hand lever 17. In the preferred operation, this said lever is shifted one notch at a time, and the hand lever 16 is then manipulated so as to bring the series of nozzles 9 to the vertical position in front of one set of flues after the other as well as inclined to a greater or less extent to insure that all of the flues will 90 be treated by the blast of steam. It is, of course, evident that the stand pipe 7 swings in an arc of a circle. To compensate for this the series of nozzles is preferably of greater length than the height of the sets of tubes, as clearly illustrated in the drawings. Moreover, by the 95 provision of the hand lever 16 and the revolute mounting of the header 8 with its nozzle 9, the nozzle may be adjusted to any diagonal rows of flues.

From the foregoing description in connection with the accompanying drawings, it will be seen that I have 100 provided a very simple, durable, and efficient construction of boiler flue blower, which may be made a permanent fixture of the boiler and drive the soot in the direction of the natural draft out through the smoke stack, thereby taking only a short period of time to 105 clean the boiler and that it may use absolutely dry steam and prevent the caking of the soot, while, when not in use, it may rest at one side of the combustion chamber and not opposite any vertical row of flues. It is to be noted that the blower does not inject the 111 steam into the flues from the front end of the boiler against the draft, which operation never effectually

cleans the boiler and which results in more consumption of coal and blows moisture into the tubes and cakes the soot, as well as reduction of the steam pressure and leaving the tubes in a more or less foul condition at all 5 times. These and other disadvantages are obviously overcome by the construction and arrangement of my device, as has been hereinbefore set forth.

Having thus described the invention, what is claimed as new is:

- 10 1. A boiler flue blower comprising a series of steam nozzles, a revoluble header carrying said nozzles, a stand pipe upon which said header is mounted, means for turning said header on the stand pipe, means for supplying steam to the header through the stand pipe, and means for swinging the said stand pipe.
- 15 2. A boiler flue blower comprising a series of steam nozzles, a header carrying said nozzles, a stand pipe upon which said header is mounted to turn, a depending rod connected to said header to turn the same, a hand lever provided with a rod having a loose connection with the first 20 named rod, whereby the header is turned, a hollow support

upon which said stand pipe is mounted to swing, a hand lever connected to said support to turn the same and swing the stand pipe, and means for supplying steam to the header through the hollow support of the stand pipe. 25

3. The combination with a boiler and its furnace and flues, of a series of steam nozzles mounted within the combustion chamber and adapted to be brought into juxtaposition with the ends of the flues, a header upon which said nozzles are mounted, a stand pipe within the combustion 30 chamber and upon which the header is mounted to turn, a supply pipe connected to said dome at one end, a hollow shaft connected to the other end of said steam pipe and passing through the door of the combustion chamber, the stand pipe being mounted upon said shaft, a quadrant, a 35 hand lever arranged for engagement with said quadrant and operatively connected to the hollow shaft to turn the same, and another hand lever connected to said header to turn the latter.

In testimony whereof I affix my signature in presence of 40 two witnesses.

THOMAS E. HUTCHINS. [L. S.]
